EXERCISING DEVICE

John A. Donato, 11039 Fitzwater Road,
Brecksville, Ohio 44141

Filed Apr. 23, 1968, Ser. No. 11,580

Term of patent 14 years

Int. Cl. D21—03

U.S. Cl. D34—5

FIGURE 1 is an elevational side view of an exercising device embodying my design, the opposite side being similar in appearance;

I claim,

The ornamental design for an exercising device, substantially, as shown and described.
